UNITED STATES PATENT OFFICE.

JOHN R. VAN WORMER, OF TOLEDO, OHIO.

FOLDED-BLANK BOX.

1,123,628.

Specification of Letters Patent.

Patented Jan. 5, 1915.

Application filed October 2, 1913. Serial No. 793,022.

To all whom it may concern:

Be it known that I, JOHN R. VAN WORMER, citizen of the United States, residing at Toledo, in the county of Lucas and State of Ohio, have invented new and useful Improvements in Folded-Blank Boxes, of which the following is a specification.

My present invention has to do with folded blank boxes; and it consists in a box fabricated from a blank without the employment of any extraneous means other than water-proof glue or other adhesive adapted to enable the box to contain and retain milk or other liquid.

The object of the invention is the provision of a perfectly sanitary box adapted to be expeditiously and economically produced immediately precedent to the placing of milk or other liquid therein, and also adapted to be readily and effectually sealed.

With the foregoing in mind the invention in all of its details will be fully understood from the following description and claim when the same are read in connection with the drawings, accompanying and forming part of this specification, in which:

Figure 1 is a perspective showing a box or bottle constructed in accordance with my invention, as sealed. Fig. 2 is a fragmentary perspective showing the mouth of the box as open. Fig. 3 is a transverse section taken vertically through the closure of the box. Fig. 4 is a plan showing the blank of which the box is formed. Fig. 5 is a section taken through the closure in the plane indicated by the line 5—5 of Fig. 3.

Similar numerals of reference designate corresponding parts in all of the views of the drawings.

The blank shown in Fig. 4 is in one piece of paper, pasteboard or other material compatible with my invention, and it is creased along the several dotted lines to form the box portions hereinafter referred to. Among these portions are the side walls 1, 2, 3, and 4, the main bottom walls 5 and 6, and the supplementary bottom walls 7 and 8, as well as an end flap 9. In the fabrication of the box, the several walls or portions 1, 2, 3 and 4 are relatively arranged to form a rectangle in plan, and the flap 9, which can be arranged at either end of the blank without affecting my invention, is arranged against the inner side of the particular side wall that is opposed to it. The supplementary bottom walls 7 and 8, which

are separated by cuts 10 from the bottom walls 5 and 6, are bent inwardly at right angles to the walls 2 and 4, and are arranged with their edges opposed. The bottom walls 5 and 6 are likewise bent inwardly against the under sides of the supplementary walls 7 and 8; one of the said bottom walls being arranged against the under side of the other, and all of the said walls being retained in position to retain the body of the box in rectangular form by waterproof glue or other adhesive applied in the conventional or any other approved manner.

In addition to the portions mentioned, the blank is creased along certain of the dotted lines shown in Fig. 4, to form the top portions 11, 12, 13 and 14 of the box, as well as the mouth portions 15, 16, 17 and 18, and the closure tongue 19. It will also be seen by reference to Figs. 2 and 4, that the top portions 11 and 13 are provided with diagonal creases 20, to form the inwardly directed folds of the box top, and that the said diagonal creases 20 merge into the vertical creases 21 of the mouth portions 15 and 17, which vertical creases 21 bring about the inward folds 22, Fig. 5, of the mouth when the box is closed. It will also be seen by reference to Figs. 2 and 5 that the mouth portions 15 and 17 are provided with indentures 23 to receive excess paraffin when the same is applied to the mouth incidental to the closing and sealing of the box. I would further have it understood at this point that when the box is closed an upstanding pocket is formed between the mouth portion 16 and the adjacent sides of the folds 22 on the mouth portions 15 and 17, into which pocket the sealing tongue 19 is inserted, as appears in Fig. 3. In this manner the box will be hermetically sealed, and at the same time a strong protuberance is provided on the top of the box which protuberance may be and preferably is employed as a handle in placing the boxes in and removing the same from the cells of compartment cases. I would have it understood, however, that when desired, the protuberance mentioned and which is numbered 25, may be folded down flat on the top of the box, this being advantageous when it is desired in packing to superimpose a number of the boxes. In the fabrication of the box it is to be understood that the blank portions forming the top and mouth of the box are to be retained in the relative ar-

angement shown in Fig. 2 by water-proof glue or other suitable adhesive suitably applied for the purpose.

My invention provides a blank that is adapted to be paraffined and fabricated into the box shown in Fig. 1 in one operation, and hence it will be manifest that the box may be expeditiously and easily produced which is materially advantageous from an economical standpoint; and it will also be manifest that subsequently to the placing of milk or other liquid in the box the same can be quickly closed and effectually sealed by placing the integral tongue 19 in the pocket hereinbefore referred to, applying paraffin or other suitable agent to the closure, either before or after the said insertion of the tongue 19, and then fluting the layers of the mouth or closure, as indicated by 26 in Figs. 1 and 3.

Having described my invention, what I claim and desire to secure by Letters-Patent, is:

A box comprising walls to form a top,

two opposite walls of the top being provided 25 with diagonal creases to form inward folds, walls extending upwardly from the first-named walls to form an upstanding mouth, two opposite walls of the mouth-forming walls having vertical creases, extending 30 from the diagonal creases and forming inward folds, and also having indentures opposed to each other and adapted to receive excess paraffin or other sealing agent, and a tongue on the upper edge of one of the unfolded mouth-forming walls and adapted to be inserted in a pocket formed between the folded mouth-forming and indenture-bearing walls and the other unfolded mouth-forming wall.

In testimony whereof I have hereunto set my hand in presence of the subscribing witnesses.

JOHN R. VAN WORMER.
